LOCK FOR SLIDING DOORS

George R. Treptow, Chicago, Ill., assignor to The Youngstown Steel Door Company, Cleveland, Ohio, a corporation of Ohio

Application July 22, 1953, Serial No. 369,677

12 Claims. (Cl. 292—148)

This invention relates to locks for sliding doors and more particularly to locks for sliding doors of railway freight cars.

It is an object of this invention to provide locks for sliding doors of the type embodying lock brackets and vertically movable locking pins wherein the locking pins shall include means capable of cooperating with the lock brackets for positively limiting vertical movement of the pins and preventing shearing of the seals used with the locking pins.

A further object is to provide locks of the character indicated in which the means for limiting vertical movement of the locking pins shall be rotatable.

A further object is to provide locks of the character indicated in which the means for limiting vertical movement of the locking pins shall be rotatable, and which shall include means for limiting rotation of the first mentioned means.

A further object is to provide locks of the character indicated and of such construction as to reduce the cost of the locks.

A further object is to provide locks of the character indicated which shall simplify the assembly of the locking pins with the lock brackets and positively prevent loss of the locking pins.

A further object is to provide locks of the character indicated wherein the pattern equipment for and construction of the lock brackets are simplified and their cost reduced.

A further object is to provide locks of the character indicated which shall permit standardization of parts of the lock brackets and their use interchangeably upon box and automobile box cars.

A further object is to provide locks of the character indicated which shall permit adjustment of the lock brackets during their initial application to the cars so as to secure full takeup of tapered locking pins carried by the lock brackets.

A further object is to provide locks of the character indicated which shall also include separate supports cooperating with the rest of the lock brackets to hold the latter in adjusted position until they are permanently secured in place.

Other objects of the invention will become clear as the description thereof proceeds.

In the drawings forming part of this specification:

Fig. 1 is a fragmentary elevation showing a lock embodying the instant invention applied to the double doors of an automobile box car.

Fig. 2 is a horizontal section taken on line 2—2 of Fig. 1.

Fig. 3 is a vertical section taken on line 3—3 of Fig. 1.

Fig. 4 is a horizontal section taken on line 4—4 of Fig. 1.

Fig. 5 is a horizontal section taken on line 5—5 of Fig. 1.

Fig. 6 is a horizontal section taken on line 6—6 of Fig. 1.

2

Fig. 7 is a side elevation of the lower portion of a locking pin with parts in position to permit the pin to be moved upwardly.

Fig. 8 is a view similar to Fig. 1 showing a lock embodying the instant invention applied to a box car.

Fig. 9 is a horizontal section taken on line 9—9 of Fig. 8.

Fig. 10 is a view similar to Fig. 8 illustrating a modified form of lock.

Fig. 11 is a vertical section taken on line 11—11 of Fig. 10.

Fig. 12 is a horizontal section taken on line 12—12 of Fig. 10.

Fig. 13 is a horizontal section taken on line 13—13 of Fig. 10.

Fig. 14 is a view similar to Fig. 7 of the lock shown in Fig. 10.

Referring first to the embodiment of the invention illustrated in Figs. 1—7 of the drawings the reference numeral 10 designates the lock bracket in its entirety.

The lock bracket is formed of two separate members 11 and 12. The member 11 is preferably a pressing which is substantially channel-shaped in section. It embodies a web 13 and legs 14 and 15 which in the illustrated embodiment slope outwardly. The member 11 is disposed within the channel-shaped portion 16 of the front

vertical reinforcement 17 of the auxiliary door 18 of the double door construction for an automobile box car.

The main door of the double door construction is indicated at 19. The member 11 is so disposed within the channel-shaped portion 16 that the web 13 of the member is spaced from the web 20 of the channel-shaped portion 16. The member 11 is secured in position as by

welding the legs 14 and 15 thereof to the channel-shaped portion 16 as shown more clearly in Fig. 2 of the drawings.

The member 12 of the lock bracket is in the form of a casting. It embodies a rear wall 21 which carries vertically spaced housing members 22 and 23 and a vertical-

40 depending flange 24 disposed at one side of the wall 21 below the lower housing member 23. The top of the rear wall 21 of the lock bracket member 12 is formed with a hook 25 shown more clearly in Fig. 3 of the drawings.

45 After the lock bracket member 11 is welded in position the lock bracket member 12 is mounted thereon and adjusted to its proper position horizontally while supported from the member 11 by means of the hook 25. Thereafter the member 12 is welded to the member 11 and to the vertical door reinforcing member 17 as shown more clearly in Figs. 1, 2 and 7 of the drawings.

Carried by the lock bracket member 12 is a locking pin 26 slidably retained upon the member 12 by means of the housing members 22 and 23 through which the locking pin slides.

50 As shown more clearly in Fig. 1 the locking pin is provided with a downwardly and inwardly sloping portion 27. The lower portion of the locking pin is provided with a recess 28 which cooperates with a substantially similar recess 29 formed in a member 30 secured as by means of welding to the lower portion of the locking pin.

55 As shown more clearly in Figs. 3 and 5 of the drawings the recesses 28 and 29 cooperate to provide a chamber 31 which rotatably receives the elongated head 32 of a lug 33.

The lower portion of the locking pin and the member 30 are shaped as illustrated in Fig. 3 of the drawings to provide a restricted opening 34 into the chamber 31.

60 The lug 33 is correspondingly formed with a neck 35 which extends through the opening so that the substantially egg-shaped body portion 36 of the lug 33 lies below the lower end of the locking pin.

65 This body portion is formed with a seal-receiving opening 37 which in one position of the lug is adapted to be aligned with a seal receiving slot 38 formed in the de-

70

pending flange 24 of the lock bracket member 12. From Fig. 5 of the drawings it will be seen that the chamber 31 is substantially elongated horizontally so that the lower portion of the locking pin and the member 30 which define the chamber 31 are adapted to be engaged by the elongated head 32 of the lug 33 in order to limit rotation of the lug to substantially 90°.

A round rod 39 is welded to the inner face at the top of the outer wall 40 of the upper housing member 22. While the round rod is preferred, it will be apparent that the wall 40 can be cast with an inwardly projecting flange as shown in Fig. 11 of the drawings. The locking pin 26 is assembled with the lock bracket member 12 after the rod 39 is welded to the upper housing member and prior to the assembly of the member 30 and the lug 33 with the locking pin. The rod 39 does not interfere with the noted assembly of the locking pin with the lock bracket member 12. After this assembly the member 30 and the lug 33 are assembled with the locking pin by welding the member 30 to the lower portion of the pin. After such assembly it will be apparent that when the lug 33 is rotated so as to lie in vertical alinement with the locking pin 26 as shown in Fig. 7 of the drawings, the pin can be moved upwardly but cannot be disengaged from the member 12 because the depth of the lower portion of the pin and the member 30 is greater than the distance from the rear wall of the member 12 to the rod 39.

In order to lock the main and auxiliary doors together when they are in closed position the locking pin 26 is adapted to engage a hasp 41 swingably carried by a hasp fastener 42 which is formed with a neck portion 43 adapted to extend through an eye 44 formed in the hasp. Forwardly of the eye 44 the hasp is formed with a housing section 45. The hasp extension beyond the housing section 45 is indicated at 46 and the extending portion is provided with a recess 47 adapted to be engaged by a lug 48 formed on lever 49 pivotally supported in a normally vertical position from the lower portion of the lock bracket member 12 as indicated at 50. To engage the hasp 41 the locking pin 26 extends through the housing section 45 so that the sloping portion 27 of the pin engages a correspondingly sloped side wall 51 of the box section of the hasp. By reason of the construction described and the indicated relationship between the locking pin and the hasp, separation between the main and auxiliary doors is prevented. In the event that these doors are not fully closed so as to be in abutment, as illustrated in Fig. 2 of the drawings, they can move toward each other. Such movement effects separation between the sloping portions 27 and 51 whereupon the locking pin drops by the action of gravity in order to restore this engagement. It is apparent, therefore, that back and forth movement of the doors and resultant wear on the parts of the lock are prevented.

When the locking pin and the hasp of the lock structure are engaged as shown in Fig. 1 of the drawings, a seal (not shown) extends through the locking pin and the flange 24 of the lock bracket member 12. To obtain this the lug 33 is rotated so that it lies substantially at a right angle to the rear wall 21 of the lock bracket member 12 and brings into alinement the opening 37 in the lug 33 and the seal slot 38 formed in the flange 24. Rotation of the lug for this purpose is limited by the engagement of the elongated head 32 with the member 30 secured to the lower portion of the locking pin. The rotation as indicated of the lug 33 in order to permit sealing of the doors disposes the lug beneath the lower housing member 23. As a result of this any forces upon the lock tending to cause the locking pin to jump upwardly will not bring about shearing of the seal since before this can occur the lug will engage the lower edge of the lower housing member 23 so as to prevent further upward movement of the locking pin.

When it is desired to unlock the two doors the seal is removed and the lug turned through approximately 90°

so that it is in vertical alinement with the locking pin. The latter can then be moved upwardly so as to be disengaged from the hasp 41 which can then be swung outwardly away from the lock bracket and downwardly so as to be supported by the hasp fastener.

By reason of the construction of the lock bracket the member 11 can be materially simplified and its cost greatly reduced. The member 12 of the lock bracket can be standardized since any variations in construction of the auxiliary door can be absorbed by the relatively simple pressing which forms member 11. The castings therefrom which the member 12 of the lock bracket are formed can be identical regardless of the variations in the structure at the front edge of the auxiliary door.

The construction of the lock bracket, moreover, permits simple adjustment of the member 12 relative to the member 11 so as to substantially simplify the securement of the lock bracket to the door while insuring initial full take-up of the lock. This is accomplished by hanging the member 12 from the web of member 11 by means of the hook 25 formed on the member 12. Locking engagement between the locking pin 26 and the hasp 41 is then obtained so as to insure full take-up of the lock by shifting the member 12 horizontally along the member 11. When the proper relationship between the locking pin and the hasp has been established the member 12 is welded to the member 11 and to the vertical reinforcing member 17 of the auxiliary door.

The provision of the rotatable sealing lug 33 provides positive assurance against breakage of seals. Furthermore, the construction at the lower portion of the locking pin by means of which the lug 33 is rotatably carried by the pin simplifies the casting forming member 12 of the lock bracket and the assembly heretofore required with other types of lock brackets. Prior to applicant's invention a lug was cast integral with the locking pin at the lower portion of the pin and an inwardly extending flange was cast integral with the upper edge of the outer wall of the upper housing member. With this construction it was necessary to cast this outer wall in the form of an outwardly curved member in order to permit assembly of the locking pin with the lock bracket. After such assembly it was necessary to hammer the curved wall inwardly so that the flange extending inwardly therefrom would be engaged by the fixed lug to prevent disengagement of the locking pin from the housing member. However, inward hammering of the curved wall was sometimes overlooked so that loss of the locking pins occurred. This is prevented by the instant invention which also permits the wall 40 to be formed straight and which eliminates the need for hammering this wall as heretofore required.

The instant invention, however, is not limited to application to the double doors of automobile box cars. The invention is illustrated in Figs. 8 and 9 applied to a box car which is equipped with single sliding doors. In this application the cast member 12 of the lock bracket is the same as that utilized in connection with the double doors of automobile box cars. The standardization of this member of the lock bracket therefore becomes apparent. However, since the box car carries a front stop member 52 adjacent to the forward edge of the door opening 53 which is adapted to limit closing movement of the door 19, the configuration of the member 11 of the lock bracket is modified. The door of the box car application is the same in construction as the main door of the automobile box car application.

The particular configuration of the member 54 of the lock bracket may be varied as desired. In the embodiment illustrated in Figs. 8 and 9 of the drawings this member, which is a pressing, embodies an outwardly extending flange 55 secured as by means of welding to the front stop member 52, a forwardly and outwardly sloping flange 56 and a rearwardly extending flange 57 which is secured as by means of welding to the front stop mem-

ber 52. The lock bracket member 12 is mounted upon the flange 57 by means of the hook 25 and when properly adjusted in order to insure full take-up of the locking pin the member 12 is welded to the flange 57 and to the front stop member 52. The locking pin utilized in the considered embodiment of the invention is the same as the locking pin heretofore described.

Another embodiment of the invention is illustrated in Figs. 10 to 14 of the drawings. In this embodiment which is illustrated as applied to a box car, the lock bracket 58 is formed of a unitary casting which is secured directly to the car as by means of rivets. The lock bracket carries vertically spaced upper and lower housing members 59 and 60. The upper housing member is flanged inwardly as indicated at 61 for the purpose of preventing loss of the locking pin. The lower housing member 60 carries the vertically disposed opening and closing lever 49 which is pivotally secured to the lower housing member.

The locking pin 62 of the considered embodiment of 26. While it is formed with a downwardly and inwardly sloping portion 63 which is adapted to engage the similarly sloping wall 51 of the hasp 41, the lower portion of the pin differs in construction from the lower portion of the pin 26. The lower portion 64 of the pin 62 is substantially cylindrical in shape and is provided with a projection 65 and a slot 66 below the projection 65 which extends entirely through the cylindrical portion. A sleeve 67 is rotatably mounted on the cylindrical portion 64 and is retained thereon by means of a cap member 68 secured as by means of welding to the cylindrical portion. The sleeve 67 is coped as indicated at 69 in order to provide shoulders 70 and 71. The projection 65 formed on the cylindrical portion 64 is seated within the coped portion 69 of the sleeve between the shoulders 70 and 71. An ear 72 is secured as by means of welding to the sleeve 67 in order to provide a finger grip for the purpose of rotating the sleeve around the cylindrical portion.

In order to assemble the locking pin 52 with the lock bracket 58 the locking pin is inserted downwardly through the housing members 59 and 60 before the sleeve 67 is secured upon the locking pin. After assembly of the locking pin with the lock bracket the sleeve 67 is then slid upon the cylindrical portion of the pin and retained thereupon by the cap member 68 which is welded to the pin. The ear 72 is welded to the sleeve 67 before the assembly of the sleeve with the cylindrical portion 64 of the pin.

The door 19 is shown in closed and locked position in Fig. 10 of the drawings. When it is desired to release the hasp 41 from the locking pin 62 in order to move the door to open position the seal (not shown) is first removed and the sleeve 67 is rotated so that the ear 72 lies in vertical alignment with the locking pin. Rotation of the sleeve 67 for this purpose is limited by the engagement of the projection 65 formed on the cylindrical portion 64 and the shoulder 70 formed on the sleeve. When this relationship between the ear 72 and the locking pin 62 has been established the pin may be moved upwardly so as to be completely disengaged from the hasp 41. The door may then be opened.

In order to lock the door after it has been moved to closed position the hasp is positioned between the upper and lower housing members and the pin is moved downwardly through the box section 45 of the hasp to the position shown in Fig. 10 of the drawings. At this time the sleeve 67 is rotated by means of the ear 72 approximately through an angle of 90° until the ear lies beneath the lower housing member 60. Rotation of the sleeve is limited by the engagement of the projection 65 with the shoulder 71 formed on the sleeve. When this has been done it will be found that the slot 66 formed in the cylindrical portion 64, the slots 73 and 74 formed

in the sleeve 67 and the slot 75 formed in a flange 76 cast integrally with the lock bracket 58 will be in alignment so that a seal (not shown) may be threaded through the slots in order to seal the door. It will be apparent that in the considered embodiment of the invention as well as the embodiments illustrated in Figs. 1 to 9, inclusive, sealing of the door can be obtained only when the ear 72 or the lug 33 lies beneath the lower housing members of the lock brackets. It is apparent that in this position of the ear 72 engagement between it and the lower housing member 60 will limit upward movement of the locking pin and thus prevent breakage of the seal.

It will be apparent that numerous changes and modifications in the details of the invention will be clear to those skilled in the art. It is intended, therefore, that all such modifications and changes be comprehended within this invention which is to be limited only by the scope of the claims appended hereto.

I claim:

1. In a lock for sliding car doors, a lock bracket having vertically spaced housing members and carrying a tapered locking pin slidable through said housing members, said locking pin comprising a body portion and a lug mounted for rotation in a horizontal plane on the lower end of said body portion, said lug in one position thereof projecting directly under the lower of said housing members at an angle to said body portion to prevent movement of said pin through said latter housing member, said lug being rotatable horizontally to a position beneath said body portion to permit movement of said pin through said housing members.
2. In a lock for sliding car doors, a lock bracket having vertically spaced housing members and carrying a tapered locking pin slidable through said housing members, said locking pin comprising a body portion and a lug mounted for rotation in a horizontal plane on the lower end of said body portion, said lug in one position thereof projecting directly under the lower of said housing members at an angle to said body portion to prevent movement of said pin through said latter housing member, said lug being rotatable horizontally to a position beneath said body portion to permit movement of said pin through said housing members, said lock bracket and said lug being provided with seal openings, said seal openings being aligned when said lug projects beneath said lower housing member, said seal openings being out of alignment when said lug is beneath said body portion of said pin.
3. In a lock for sliding car doors, a lock bracket having vertically spaced housing members and carrying a tapered locking pin slidable through said housing members, said locking pin comprising a body portion and a lug mounted for rotation in a horizontal plane on the lower end of said body portion, said lug in one position thereof projecting directly under the lower of said housing members at an angle to said body portion to prevent movement of said pin through said latter housing member, said lug being rotatable horizontally to a position beneath said body portion to permit movement of said pin through said housing members, and means on said lug engageable with said pin for limiting rotation of said lug between said positions.
4. In a lock for sliding car doors, a lock bracket having vertically spaced housing members and carrying a tapered locking pin slidable through said housing members, said locking pin comprising a body portion having a chamber at the lower end thereof provided with a restricted opening and a lug projecting below said body portion, said lug having a head seated in said chamber and rotatable in a horizontal plane therein, a restricted neck lying in said chamber opening and a body portion adapted to project directly under the lower of said housing members, said lug being rotatable horizontally to position said body portion of said lug beneath the body portion of said pin to permit movement of said pin through said housing member.

5. In a lock for sliding car doors, a lock bracket having vertically spaced housing members and carrying a tapered locking pin slidable through said housing members, said locking pin comprising a body portion having a chamber at the lower end thereof provided with a restricted opening and a lug projecting below said body portion, said lug having a head seated in said chamber and rotatably in a horizontal plane therein, a restricted neck lying in said chamber opening and a body portion adapted in one position thereof to project directly under the lower of said housing members, said lug being rotatable horizontally to position said body portion of said lug beneath the body portion of said pin to permit movement of said pin through said housing member, said head of said lug having means engageable with said chamber 15 for limiting rotation of said lug between said positions.

6. In a lock for sliding car doors, a lock bracket having vertically spaced housing members and carrying a tapered locking pin slidable through said housing members, said locking pin comprising a body portion having a chamber at the lower end thereof provided with a restricted opening and a lug projecting below said body portion, said lug having a head seated in said chamber and rotatably in a horizontal plane therein, a restricted neck lying in said chamber opening and a body portion adapted in one position thereof to project directly under the lower of said housing members, said lug being rotatable horizontally to position said body portion of said lug beneath the body portion of said pin to permit movement of said pin through said housing member, said head of said lug having means engageable with said chamber 20 for limiting rotation of said lug between said positions, said body portion of said lug and said lock bracket having seal openings said seal openings being alined when said body portion of said lug projects under said lower housing member, said seal openings being out of alinement when said lug is beneath said body portion of said pin.

7. In a lock for sliding car doors, a lock bracket having vertically spaced housing members and carrying a tapered locking pin slidable through said housing members, said locking pin comprising a body portion, said body portion having a cylindrical portion at the lower end thereof, a lug mounted for rotation in a horizontal plane on said cylindrical portion, said lug being adapted in one position thereof to project beneath the lower of said housing members, said lug being rotatable horizontally to a position beneath said body portion to permit movement of said pin through said housing members, and means for retaining said lug upon said cylindrical portion.

8. In a lock for sliding car doors, a lock bracket having vertically spaced housing members and carrying a tapered locking pin slidable through said housing members, said locking pin comprising a body portion, said body portion having a cylindrical portion at the lower end thereof, a lug mounted for rotation in a horizontal plane on said cylindrical portion, said lug being adapted in one position thereof to project beneath the lower of said housing members, said lug being rotatable horizontally to a position beneath said body portion to permit movement of said pin through said housing members, means for retaining said lug upon said cylindrical portion, and cooperating means on said pin and said lug for limiting rotation of said lug between said positions.

9. In a lock for sliding car doors, a lock bracket having vertically spaced housing members and carrying a tapered locking pin slidable through said housing members, said locking pin comprising a body portion, said body portion having a cylindrical portion at the lower end thereof, a

lug mounted for rotation in a horizontal plane on said cylindrical portion, said lug being adapted in one position thereof to project beneath the lower of said housing members, said lug being rotatable horizontally to a position beneath said body portion to permit movement of said pin through said housing members, and means for retaining said lug upon said cylindrical portion, said lock bracket, cylindrical portion of said pin and lug being provided with seal openings, said seal openings being alined when said lug projects beneath said lower housing member said seal opening in said lug being out of alinement with said seal openings in said cylindrical portion and said lock bracket when said lug is beneath said body portion of said pin.

10. In a lock for sliding doors of railway cars, a lock bracket comprising a base member and a separate body member provided with vertically spaced housing members and carrying a locking pin slidable through said housing members, said base member being secured to a car prior to the securement of said body member, said body member being subsequently secured to said base member, the construction of said base member being modified as required by the construction of the car to permit securement thereto, said base member always embodying a flange extending at an angle and being secured to said car and a flange spaced horizontally from said car, said body member being of the same construction regardless of the construction of the base member and being capable of securement to the latter flange of all embodiments of said base member.

11. In a lock for sliding doors of railway cars, a lock bracket comprising a base member and a separate body member provided with vertically spaced housing members and carrying a tapered locking pin slidable through said housing members, said body member having a hook engageable with said base member to support said body member upon said base member for horizontal movement relative thereto, said base member being secured to a car prior to the securement of said body member, said body member being subsequently secured to said base member, and said base member being modified as required by the construction of the car to permit securement thereto, said base member always embodying a flange extending at an angle and being secured to said car and a flange spaced horizontally from said car, said body member being of the same construction regardless of the construction of the base member and being capable of securement to the latter flange of all embodiments of said base member.

12. In a box car having a sliding door and a front stop for limiting closing movement of the door, a base member welded to said car adjacent to said front stop, and a separate body member comprising vertically spaced housing members and carrying a locking pin slidable through said housing members, said body member being provided with a hook engageable with said base member to support said body member upon said base member for horizontal movement relative thereto, and means securing said body member to said base member after said base member has been welded to said car.
